SUPPORTING MECHANISM

Ira M. Coppock, Dayton, Ohio, assignor of five one-hundredths to N. Douglas Parker, Jr., Washington, D. C., thirty-two one-hundredths to Homer D. Humphrey, and thirty-two one-hundredths to George S. Blackmore, both of Pittsburgh, Pa.

Application January 19, 1938, Serial No. 185,775

6 Claims. (Cl. 217—60)

This invention relates to supporting mechanism for hinged closures and more particularly to a mechanism for supporting an automobile hood or trunk lid.

5 One of the objects of the present invention is to provide a novel supporting mechanism for hinged closures of the type which may be automatically locked and unlocked, thus dispensing with all manual operations except that of merely 10 raising and lowering the closure.

Another object is to provide a mechanism of the above character which shall be positively acting at all times, capable of economical manufacture and readily adaptable to closures of various 15 shapes and sizes.

Other objects and novel features of the invention will appear more fully hereinafter from the following detailed description when taken in connection with the accompanying drawing illustrating 20 one form of the invention. It is to be expressly understood, however, that the drawing is utilized for purposes of illustration only and is not designed as a definition of the limits of the invention, reference being had for this purpose 25 to the appended claims.

In the drawing:

Fig. 1 is a side view of a supporting mechanism constructed in accordance with the principles of the present invention;

30 Fig. 2 is a side view of the supporting mechanism in Fig. 1 and illustrating the same in folded position, the dotted-line portions of this figure showing the mechanism as it approaches folded position, and

35 Fig. 3 is an end view of the supporting mechanism when folded.

Referring more particularly to Fig. 1, the supporting means of the present invention is illustrated therein as including a pair of arms 4 and 5 pivotally connected together as by means of a pin 6. The free end of arm 4 is pivoted on a pin 7 carried by a bracket 8 secured in any suitable manner to a vehicle trunk lid or hood, a portion of which is indicated at 9. The free 45 end of arm 5 is connected to a bracket 10, carried by a stationary portion 11 of the vehicle, as by means of a pin and slot connection, the latter being formed by a slot 12 provided in the arm 5 and a pin 13 carried by the bracket 10. It will 50 be understood that the trunk lid or hood is hingedly connected with the stationary portion 11 in a well known manner. A tension spring 14, having its opposite ends associated with the pin 13 and a stud 15 carried by the arm 5 adjacent its 55 outer extremity, normally tends to move the arm

5 to such a position that the lower end of the slot 12 is in engagement with pin 13. As shown in full lines in Fig. 1, however, the weight of the trunk lid 9 is such that the upper end of slot 12 engages the pin 13 and the spring 14 is thus 5 in its extended position.

In order to prevent pivotal movement of the arm 5 in one direction, when the arms 4 and 5 are in extended supporting position, a dog 16 is pivoted to the bracket 10 as by means of pin 10 17, the said dog being provided with forward and rear lobes 18 and 19 for a purpose which will appear more fully hereinafter. This dog is capable of movement in a predetermined arc during operation of the supporting mechanism, and, as 15 shown, a flange 20 is provided which limits the arc of movement of the dog in opposite directions. This will be clear when it is considered that, in Fig. 1, one extreme movement of the dog is illustrated wherein the portion 21 thereof engages 20 the flange 20, while, in Fig. 2, the dog is moved to the other extremity of its movement wherein portion 22 engages flange 20. Movement of the dog 16 in its two extreme positions of arcuate 25 movement is accomplished by providing a rounded end 23 upon the lower extremity of arm 5, together with a shoulder 23a, it being understood that such end and shoulder cooperate with the lobes 18 and 19 of the dog 16 to move the latter in a manner which will appear more fully herein- 30 after.

In order to yieldably maintain the dog in its two extreme positions of movement, a flat leaf spring 24 is secured to the bracket 10 as by means of an anchor 25, the spring 24 extending from 35 the anchor and having its outer portion formed in such a manner as to either engage a notch 26 formed in the dog or engage the surface 21 thereof, as will be seen from Figs. 1 and 2. As will be perceived from Fig. 1, the anchor 25 moreover serves to prevent pivotal movement of the arm 5 in a counterclockwise direction about the pin 13.

Referring to the folded position of the supporting mechanism as illustrated in Fig. 2, it will 45 be understood that the dog 16 is yieldably maintained in a non-supporting position by the spring 24 bearing against the portion 21 of the dog. As the trunk lid or hood having the end of the arm 4 pivotally connected thereto is raised, the 50 mechanism takes the position shown in dotted lines in Fig. 2, and, from this figure, it will be perceived that the extremity 23 of the arm 5 approaches and contacts the lobe 18 of the dog. Upon continued upward movement of the lid, the 55

extremity 23, in contact with the lobe 18, will move the dog 16 a slight amount in a clockwise direction about pivot 17, such extent of movement, however, being insufficient to bring notch 26 into registry with the end of spring 24. When the extremity 23 clears the end of lobe 18, the spring 24 will resiliently maintain the dog in contact with the shoulder 23a. As the arms 4 and 5 take the load of the supported member, arm 5 will slide downwardly, due to the pin and slot connection 12 and 13 and will positively move the dog in a clockwise direction about pivot 17 until the upper end of the slot 12 contacts the pin 13. At this point, the parts are so proportioned that the end of spring 24 will drop into notch 26 and, at the same time, portion 21 of the dog will be in contact with the stop flange 20. Simultaneously with the above operations, extremity 23 will contact the spring anchor 25, as shown in Fig. 1, and the arm 5 will thus be locked in an extended supporting position.

If it be desired to lower the lid or hood member 9, it is only necessary to move the supported member upwardly a sufficient distance to enable extremity 23 to clear lobe 18. Under these conditions, pivots 6 and 7 will respectively take the positions 6a and 7a indicated on Fig. 1. With the parts in such position, continued lowering of the lid will cause the pivotal connection 6 between the arms 4 and 5 to move in the direction of the arrow a and the arm 5 will move in a clockwise direction about the pivot pin 13. During this last named movement, the spring 14 moves the arm 5 so that the lower end of slot 12 contacts the pin 13. As will be readily perceived from Fig. 1, the extremity 23 of the arm 5 engages the lobe 19 of the dog and positively moves the latter to the position shown in Fig. 2 where the portion 22 abuts the stop flange 20. The spring 24 contacting the edge of the dog yieldably maintains the latter in this position. Continued downward movement of the lid serves to move the arms 4 and 5 into a folded position, as shown in Fig. 3 and in full lines in Fig. 2.

It will be observed from Fig. 1 that the construction of the parts, including the location of the spring anchor 25, is such that the pivotal connection 6 is but slightly displaced from the center line drawn between the two pivots 7 and 13. This arrangement insures that the arms 4 and 5 will be substantially in straight compression, thus relieving the parts of bending moments when the supporting mechanism is in supporting position.

While a preferred embodiment of the invention has been described herein with considerable particularity, it is to be understood that the invention is not limited thereto but may be embodied in various forms as will be readily apparent to those skilled in the art. Reference will, therefore, be had to the appended claims for a definition of the limits of the invention.

What is claimed is:

1. In a device of the character described, comprising a supporting arm, a bracket, means for pivotally and slidably mounting one end of said arm on the bracket, a dog pivotally mounted on the bracket for limited pivotal movement in opposite directions, means on the end of said arm for moving the dog to the limit of its movement in one direction during slidable movement of the arm, said dog when so moved cooperating with the end of said arm for preventing pivotal movement of the latter in one direction, a leaf spring cooperating with said dog for resiliently main-

taining the latter in said moved position, and an anchor for said spring serving to prevent pivotal movement of the arm in the opposite direction.

2. In a device of the character described, comprising a supporting arm, a bracket, means for pivotally and slidably mounting one end of said arm on the bracket, a dog pivotally mounted on the bracket for limited pivotal movement in opposite directions, means on the end of said arm for moving the dog to the limit of its movement in one direction during slidable movement of the arm, said dog when so moved cooperating with the end of said arm in one direction for preventing pivotal movement of the latter in one direction, means cooperating with said arm for preventing pivotal movement of the latter in the opposite direction, a leaf spring anchored to said bracket and contacting said dog for holding the latter in said moved position during sliding movement of the arm in the opposite direction, and resilient means normally tending to move the arm in said opposite direction.

3. In a device of the character described, comprising a pair of pivotally connected arms adapted to support a hinged lid, a bracket, means including a pin and slot connection for pivotally and slidably connecting the free end of one arm to said bracket, resilient means interconnecting said one arm and pin and normally tending to maintain a predetermined relation between said one arm and pin, means for preventing pivotal movement of said one arm in one direction including a dog pivoted on the bracket and having a portion cooperating with the free end of said one arm, said dog being moved to a predetermined position by said one arm during slidable movement thereof in one direction, means cooperating with said arm for preventing pivotal movement of the latter in the opposite direction, and a leaf spring in constant contact with said dog for resiliently maintaining the latter in said predetermined position.

4. In a device of the character described, comprising a pair of pivotally connected arms adapted to support a movable member with relation to a stationary member, one of said arms being pivotally connected to one member and the other of said arms being provided with a slot adjacent one end, a bracket secured to the other of said members, a pin carried by the bracket and extending through said slot, said pin and slot thereby enabling pivotal and slidable movement of said other arm with respect to the bracket, and means for preventing pivotal movement between said arms when the latter are extended to supporting position comprising a dog pivoted to said bracket and cooperating with said end of the other arm for movement thereby to a predetermined latching position during slidable movement of said other arm in one direction, an abutment on the bracket cooperating with said end of said other arm when the latter is slidably moved in said one direction, and a leaf spring cooperating with said dog for resiliently maintaining the dog in said latching position.

5. In an automatically operable supporting mechanism of the type having a pair of pivotally connected arms, one of the arms being pivoted to one relatively movable member while the free end of the other arm is slidably and pivotally connected with another relatively movable member, a locking dog pivoted to one of said members, means for limiting the range of pivotal movement of said dog in opposite directions, the free

end of said other arm contacting said dog and moving the latter to the limit of its pivotal movement in one direction during slidable movement of said other arm in one direction, whereby the 5 arms are supported in extended position, and a leaf spring anchored to one of said members and cooperating with said dog for resiliently maintaining the latter in said supporting position.

6. In a device of the character described, comprising a pair of pivotally connected arms adapted to support a movable member with relation to a stationary member, one of said arms being pivotally connected to one member and the other of said arms being provided with a slot adjacent one end, a bracket secured to the other of said members, a pin carried by the bracket and extending through said slot, said pin and slot thereby enabling pivotal and slidable movement of said other arm with respect to the brack-

et, resilient means connecting said pin and said other arm and tending to maintain said other arm in such position that one end of said slot engages the pin, and means for preventing pivotal movement between said arms in one direction when the latter are extended to supporting position comprising a dog pivoted to said bracket and cooperating with said end of the other arm for movement thereby to a predetermined latching position during slidable movement of said 10 other arm in a direction to move the opposite end of said slot against said pin, means cooperating with said other arm for preventing pivotal movement between said arms in the opposite direction when said dog is moved to latching position, and a leaf spring cooperating with said dog for resiliently maintaining the latter in said latching position. 15
